UNITED STATES PATENT OFFICE.

GEORGE E. KNEPPER, OF ALTOONA, PENNSYLVANIA.

REFRIGERATOR-CAR.

1,037,152.

Specification of Letters Patent. Patented Aug. 27, 1912.

Application filed December 15, 1911. Serial No. 665,916.

To all whom it may concern:

Be it known that I, GEORGE E. KNEPPER, a citizen of the United States, residing at Altoona, in the county of Blair and State 5 of Pennsylvania, have invented certain new and useful Improvements in Refrigerator-Cars, of which the following is a specification.

This invention relates to the subject of 10 car refrigeration, and has for its object improved means for obtaining a low temperature within the car, through the medium of combined ice and brine tanks used in connection with absorption or circulating coils.

15 The primary object of this invention is to provide improved means whereby refrigeration is uniformly maintained throughout the car at a much less cost than present refrigeration facilities can offer.

20 With this end in view the invention contemplates a refrigerating device, consisting essentially of the novel arrangement of combined ice and brine tanks used in piped relation with a system of absorption coils 25 or radiators.

Another object of the device is to provide improved means for retaining the brine in the brine tanks, and absorption coils or 30 radiators, thus obviating the necessity of providing additional tanks for the collection and storage of salt water drippings to be drawn off at terminal or other points.

Another object of this device is to provide means whereby the full cooling value 35 of the ice placed in the ice tanks can readily be obtained, since the gradual melting of the ice, forming a freezing mixture with the brine circulates through the absorption coils, thus absorbing the heat from the car as the 40 circulation continues, due to a difference in temperatures of the top and the bottom of the ice tanks.

Another object of this device is to provide means for regulating the flow of brine 45 through the absorption coils, thus providing in a very practical way, means whereby various degrees of temperature can readily be obtained.

A further object of this device is to provide means whereby the car can readily be heated by forcing hot water, or steam, through the coils or radiators, thus providing for the safe transportation of perishable commodities during the winter months.

55 With these and many other objects in view, which will be more readily apparent,

as the nature of the invention is better understood, the same consists in the novel construction, combination and arrangement of parts, as will be hereinafter more fully illustrated, pointed out and claimed. 60

It will be readily understood that this invention is naturally susceptible to a wide range of structural modification, without departing from the scope or spirit of the 65 invention, but a preferred and thoroughly practical embodiment thereof is shown in the accompanying drawings, in which,

Figure 1, is a cross-sectional view of a car showing the present invention installed 70 therein. Fig. 2, is a sectional view of the car taken on the line 2—2 of Fig. 1. Fig. 3, is a sectional view taken on the line 3—3 of Fig. 1. Fig. 4, is a sectional view of the valve used for drawing off and cleaning out 75 the brine, or ice tank, when such action is necessary. Fig. 5, is a front elevational view of the valve shown in Fig. 4.

Like reference numerals indicate corresponding parts throughout the several figures of the drawings. 80

In carrying out the present invention no material change in the car is contemplated, but instead of the usual means employed for refrigeration there is preferably provided a 85 plurality of ice receptacles, or tanks, designated by the numeral 10. These tanks are preferably rectangular at the base 11, with diverging sides which terminate at the top 12 of the car, as clearly illustrated in Figs. 90 1 and 3 of the drawings. To provide for the introduction of ice, into the ice tank, there is placed an opening 13 adapted to be closed by a hatch-way 14. In order to fill the tank 10, the cover or hatch-way 14, 95 is removed and ice is thrown in on the inclined surface 15 of the tank, from whence it readily slides down first filling the rectangular bottom portion 11. At this time a non-freezing liquid called "brine" is introduced and the ice tank filled with ice. When filling the tanks the first time, brine 100 in sufficient quantity to fill the radiators is preferably introduced, in order to facilitate refrigeration. I prefer to provide the inside wall 16, of the tank 10, with a plurality of screen covered openings, the lower one 17 of which communicates, through pipe connections, with the bottom portion of a radiator, designated in its entirety by the 110 numeral 19, while the upper opening communicates through a similar pipe connection

20, with the top of the radiator. I have, by preference, shown the usual form of radiator which is built up of various sections 21, and held together in the usual manner, as this form of radiator exposes the maximum surface to the air to be cooled. In connection with this system of car refrigeration, I employ therewith a draw-off pipe 30, through which the brine in the tanks may be allowed escape by way of pipe 23, which is provided with a cut-out valve 24, adapted to be controlled from the top of the car, through the medium of the handle 25, when the valve 24 is closed and the tanks filled with ice and brine, as intended, the brine rises through pipes to the top 26 of an emergency over-flow pipe 27, through which it can escape to the bottom of the car C and down the spout c to the trap 28, as shown in Fig. 3 of the drawings, without the egress of air. If the valve 24 is open, the brine will rise to the top 29 of the absorption coils, or radiators, and pass out through pipes 30, to the trap 28.

25. The tank compartments 31, are preferably provided with a strong lattice protection 32, while the openings 33 therein are filled with current deflecting shields 34, which serve to deflect rising currents of 30 warm air, downward along the ice tank, thus cooling the same in a very efficient and practical manner. At the top of the lattice protection there is preferably located a hinged door 35, which may be swung open, 35 if desired, after filling the ice receptacles; and also used as a means of ventilation when no ice is used.

The bottom of the tank 36 is provided with an outlet valve 37, which is adapted to be screwed into a flanged threaded collar 38, attached to the side 39 of the tank. The said valve 37 is provided on its head portion with a rectangular projecting stud 40 that may be used in connection with a key, wrench, or other similar tool for reciprocating the stem of the valve within the threaded collar 38. The stem of the valve 37, is provided with an oblong opening 41, through which the brine in the tank is afforded means of escape when the stem is reciprocated by means above mentioned. The slot, or opening, 41, affords a very efficient means of protecting the workman, or operator, from the direct discharge of brine, as the case would be if the slot, or opening, was not provided.

In operating this refrigerating device may be described as follows: Ice and brine are placed in the tank, as previously described, and the hatch-ways closed. The warm air from the interior of the car comes in direct contact with the absorption coils, the cold brine in the radiators, or coils, absorbing the heat in the car. Further, as the ice melts, thus providing in a very practi-

cal way, more brine for the absorption coils, or radiators, the same gradually rises in the radiators, and will so continue until the radiators are full, at which time the temperature in the top of the radiators is higher than that in the bottom of the radiators, due to the warm air of the interior of the car coming in contact with the cold radiators, or absorption coils. From this it will be obvious that a circulation of brine will be maintained between the top and the bottom of the radiators, through the tank, due to a difference in temperatures. It will also be obvious that the moisture in the car will be collected on the radiators, thus maintaining dry air throughout the interior of the car.

Having thus described my invention, and believing that the same can readily be understood without further elaboration, what I claim as new and desire to secure by Letters Patent is:

1. A refrigerating device for cars comprising a tank provided with inlet openings, and having two oppositely disposed compartments, said compartments forming a housing therebetween, radiating coils in communication with said compartments and located in the housing formed thereby, and a valve device for emptying the contents of said tank.

2. A refrigerating device for cars comprising a tank provided with inlet openings and having two oppositely disposed compartments, said compartments forming a housing therebetween, radiating coils in communication with said compartments and located in the housing formed thereby, an overflow device in communication with the radiating coils, and a valve device for emptying the contents of said tank.

3. A refrigerating device for cars comprising a tank provided with inlet openings and having two oppositely disposed compartments, said compartments forming a housing therebetween, radiating coils in communication with said compartments and located in the housing formed thereby, said radiating coils having upper and lower connections with each compartment, means shielding the opening of each connection to prevent clogging thereof, an over-flow device in communication with the radiating coil, means for lowering the level of the brine in the tank, and a valve for emptying the entire contents of the tank and coils.

4. A refrigerating device for cars comprising a tank provided with inlet openings and having two oppositely disposed compartments, said compartments forming a housing therebetween, radiating coils in communication with said compartments and located in the housing formed thereby, a casing surrounding said tank and coils provided with openings for admitting air currents to the refrigerated surfaces, an over-

flow pipe in communication with the coils, said pipe extending downwardly and discharging on the floor of the car, a draw-off connection also in communication with the 5 coils, said connection serving to reduce the level of brine below the point where the over-flow pipe connects with the coils, a valve located in the draw-off connection, a trap at the end of said draw-off connection 10 and a valve for emptying the contents of the tank.

5. In a refrigerator car, the combination with the car body, of a brine tank, a housing arranged inside of the tank, and a radiator arranged inside of the housing, said 15 radiator having separate top and bottom

brine circulating connections in communication with the interior of the tank.

6. In a refrigerator car, the combination with the car body, of a brine tank, a housing arranged within the brine tank, and a radiator arranged within the housing and having top and bottom brine circulating connections with the opposite walls of the housing and in communication with the interior of the tank. 20 25

In testimony whereof I affix my signature in presence of two witnesses.

GEORGE E. KNEPPER.
